FRONT PANEL FOR A MERCHANDISING MACHINE

Walter L. Koch, 15 Seymour St., Caldwell, N.J. 07006, and Robert P. Franklin, 23 Woodlawn Terrace, R.C. 1, Jefferson Township, N.J.

Filed July 8, 1971, Ser. No. 160,967

Term of patent 14 years

Int. Cl. D20—01

U.S. Cl. D52—3

FIG. 1 is a front perspective view of a front panel for a merchandising machine showing our new design;

FIG. 2 is an enlarged sectional view as taken from line 2—2 of FIG. 1.

We claim:

The ornamental design for a front panel for a merchandising machine, substantially as shown and described.
